UNITED STATES PATENT OFFICE.

DANIEL F. SELZER AND HENRY SELZER, OF AKRON, OHIO.

PUMP.

SPECIFICATION forming part of Letters Patent No. 518,356, dated April 17, 1894.

Application filed July 27, 1892. Serial No. 441,410. (No model.)

To all whom it may concern:

Be it known that we, DANIEL F. SELZER and HENRY SELZER, citizens of the United States, residing at Akron, in the county of 5 Summit and State of Ohio, have invented a new and useful Pump, of which the following is a specification.

This invention relates to pumps; and it has for its object to provide an improved pump 10 which is particularly adapted for pumping acid and alkaline liquors from carboys and other vessels in dispensing such liquids in drug stores.

To this end the invention contemplates an 15 improved pump of this character which not only answers every purpose of ordinary lift pumps, but at the same time provides by its particular construction against any leakage which might occur.

20 With these and many other objects in view which will readily appear as the nature of the invention is better understood, the same consists in the novel construction, combination and arrangement of parts hereinafter more 25 fully described, illustrated and claimed.

In the accompanying drawings:—Figure 1 is a side elevation of an acid pump constructed in accordance with this invention. Fig. 2 is a vertical longitudinal sectional view of the 30 same. Fig. 3 is an enlarged sectional view of the pump cylinder. Fig. 4 is a similar view of the packing box in the top of the upper reservoir.

Referring to the accompanying drawings:— 35 A represents the pump cylinder or barrel constructed of hard rubber or other suitable material which will not be affected by acids or other chemicals in connection with which the pump is used, and the same is provided with 40 an inner shoulder B near its lower end, and with a lower interiorly threaded portion C extending from a point near said shoulder to the extreme end of said cylinder or barrel. The said cylinder is further provided near 45 said lower end with a series of inlet perforations D, and is designed to receive the lower ring d secured to the cushion cap or rest E, made of soft rubber and removably inserted in the lower end of the cylinder, the same being 50 designed to serve as a cushion for the pump to rest upon without injury to the car-

boy or other vessels from which the chemical is being pumped.

As illustrated in the drawings the cushion rest E, is of a smaller diameter than the cylinder A, into the lower end of which the same is inserted, and the inner portion of said cap or rest, which is perforated for the passage of fluid therethrough, stands in from the inner threaded end of the cylinder and away from the perforations D, so as to leave a free inlet 60 for the chemicals to be pumped, and said perforated cap or rest is held removably in position by means of the exteriorly threaded collar or bushing d, surrounding the same and 65 engaging the threads of the cylinder. A valve disk F rests against the inner shoulder B of said cylinder or barrel and is provided with an ordinary flap valve f designed to work upwardly. The said valve disk is seated on 70 the supplemental unthreaded valve supporting disk G, having a central valve opening, and designed to be held closely against the main valve disk, and therefore form a tight valve joint within the cylinder, by means of 75 the threaded follower collar H. The said threaded follower collar H engages the lower interiorly threaded end of the cylinder and works against said valve supporting disk so as to hold the same firmly to its place, while 80 at the same time allowing for the ready removal of the valve. The extreme upper end of the cylinder or barrel A is exteriorly threaded as at a, and is removably connected with the distributing chamber I. The said chamber I is provided with an upper exteriorly threaded end i, which receives the removable cap J, which cap is provided with a central opening K and an exteriorly threaded neck L, surrounding said opening upon the top of 90 the said cap and forming a packing seat. A soft rubber combined packing and wiper sleeve M, snugly fits within the inclosed seat of said exteriorly threaded flange of the cap and is itself provided with the upper and 95 lower short reduced sleeve-necks N, the lower of which is elongated and projects through the central perforation K in the top of said cap, while the upper reduced sleeve neck is designed to be compressed by the supplemental smaller packing or compression cap, O 100 interiorly threaded to engage said exteriorly

threaded neck and is provided with a central 1
tapered opening P, which as the said cap is
screwed upon said neck fits over and com-
presses the upper reduced sleeve neck of the
5 packing sleeve as tightly as desired against
the plunger rod Q, moving through said pack-
ing sleeve, the said chamber and lower cylin-
der or barrel. It will be readily seen that by
the packing just described, which may be
10 termed adjustable, the packing sleeve can be
tightened as tightly as desired around the
plunger rod in order to effectually prevent any
leaking at such points. It will be apparent
that the sleeve M, is specially adapted to a
15 pump of this character in which it is abso-
lutely necessary that any leaking or spouting
of the liquids around the plunger rod shall
be positively avoided, inasmuch as the char-
acter of the chemicals pumped may be such
20 as not only to destroy clothing, but also in-
jurious and painful to the hands. The sleeve
therefore not only serves as a packing but
also as a wiper, to wipe the rod and keep the
outside portion of the same always free from
25 the chemicals which surround it in the pump.
The plunger rod Q is preferably a rubber in-
closed steel rod, but of course, may be any
other suitable material unaffected by acid or
alkaline, the said rod being provided at its
30 upper outer end with the operating knob R,
and is removably connected at its inner end
within the cylinder or barrel to the hollow
plunger S moving therein. The said plunger
S is also constructed of materials similar to
35 the other parts of the pump, and is provided
at one end with a series of escape openings
T, and its other lower end with the valve
openings U over which works the rubber ball
valve V, which closes, when the plunger is
40 moving up to lift the chemical and opens on
the down stroke thereof to allow the chemi-
cal to fill the cylinder above the plunger and
the plunger itself as will be at once apparent.
The liquid lifted into the upper larger liquid
45 chamber is drawn therefrom through an or-
dinary faucet W, and when through using
the pump, the same can be quickly emptied
of any liquid therein by turning the same up
side down and allowing the liquid to drain
50 off through the capped opening X, arranged
near the top of the distributing chamber.

From the foregoing it is thought that the
construction and operation of the herein de-
scribed chemical pump will be apparent with-
out further description, and although the 55
specific packing devices herein described are
not made the subject matter of a claim in the
present application, we will have it understood
that such packing devices may form the sub-
ject matter of a subsequent application for a 60
patent.

Having thus described our invention, what
we claim, and desire to secure by Letters Pat-
ent, is—

1. In a chemical pump, the acid proof cyl-
inder having a lower interiorly threaded end
and a series of inlet perforations in such end,
a valve removably clamped within the cylin-
der above the perforations, a flexible cushion
cap or rest arranged within the lower end of 65
the cylinder and of a smaller diameter than
the cylinder to stand in and away from the
inlet perforations, an exteriorly threaded
bushing ring fitting said cap or rest and re-
movably engaging the threads of the cylin- 70
der below the inlet perforations, and a hollow
acid proof valved plunger moving within the
cylinder, substantially as set forth.

2. In a pump, the combination of the cyl-
inder or barrel having the lower interiorly 80
threaded end, perforations in such end, and
an inner shoulder arranged above said per-
forations, a flap valve-disk adapted to rest
against said inner shoulder, an unthreaded
valve supporting disk bearing against said 85
flap-valve disk, a threaded follower-collar en-
gaging said interiorly threaded end of the
cylinder and working against said unthread-
ed disk, a flexible cushion rest or cap of
smaller diameter than the cylinder and re- 90
movably fitted in the lower end thereof below
and in from the inlet perforations, and a
valved hollow plunger moving in said cylin-
der above the valve, substantially as set forth.

In testimony that we claim the foregoing as 95
our own we have hereto affixed our signatures
in the presence of two witnesses.

DANIEL F. SELZER.
HENRY SELZER.
